APPARATUS FOR CENTERING SHOE SOLES
AND THE LIKE

John H. Flink, Watertown, Mass., assignor to The
B. F. Goodrich Company, New York, N. Y., a
corporation of New York

Application March 2, 1942, Serial No. 432,973

10 Claims. (Cl. 12—40)

This invention relates to apparatus for positioning or locating articles with reference to a given area of a supporting platform, as for centering articles preparatory to a die-stamping operation or the like, and is especially adapted for locating in succession a number of articles varying either in size or in shape or in both size and shape. The invention is designed particularly for centering shoe soles of varying sizes and configurations preparatory to stamping them with a die.

In my copending application, Serial No. 426,737, filed January 14, 1942, I have described how a middle sole for a so-called platform type sandal or slipper may be given increased flexibility by stamping the ball and toe portion of the sole with a die of a particular design in order to rearrange the surface fibers, or similar materials of construction, in a particular and predetermined manner. In quantity production operations it is difficult to center successive middle soles accurately on the support member prior to stamping them with the die, and this difficulty is particularly acute when the soles are of varying sizes. Accordingly, I have invented an apparatus for centering the middle soles, no matter what their size and configuration, preparatory to stamping them with the die so that the die will strike every sole in the same relative region. This apparatus may also be used with other objects for locating them in the same position relative to a given area of a supporting member, preferably preparatory to acting upon them by an outside agency.

The apparatus of this invention, as exemplified by a preferred embodiment, comprises a pair of locating members movably supported by a surface member for movement toward and away from each other, means for normally holding said locating members in close relation to each other, and a third locating member movable with relation to said supporting surface member and adapted to be positioned in respect to said supporting surface member by an article inserted between the first locating members, and means controlled by movement of said pair of locating members for determining the position of said third locating member when the article is inserted between the said pair of locating members. This apparatus is so constructed and arranged that an article inserted between the pair of locating members is stopped by the third locating member, whose position is determined by the position of the pair of locating members, so that each successive article inserted is always in the same relative position with respect to a given area of the surface member. Through the use

of this apparatus, it is possible for an outside instrument such as a die acting on the inserted articles to contact successive articles in the same relative region.

5 As stated hereinabove the apparatus of this invention is particularly useful for positioning middle soles of shoes preparatory to stamping such soles with a die. This embodiment will be described herein in considerable detail with reference to the accompanying drawing, of which

Fig. 1 is a plan view of the apparatus in a preferred form with portions broken away for clarity of illustration;

Fig. 2 is a vertical section taken along the line 15 2—2 of Fig. 1;

Fig. 3 is a top view of a finished middle sole which has been inserted in the apparatus of this invention and has been acted upon by a grooving die.

In the illustrated embodiment of this invention, the apparatus consists of a rectangular base member 10 and a similarly shaped rectangular top member 11 held in spaced relationship with the base member 10 by means of a spacer member 12 placed between them at the rear of the apparatus. In and on the top member 11 are three interacting positioning members comprising two studs 13, 13 extending through slots 14, 14 in the top member, and a back stop bar 15 resting on the top member 11 arranged so that it can slide on the top member 11. One of the studs 13 is mounted on an arm 23 of a substantially right-angled bell crank 16 and the other stud 13 is mounted on an arm 21 of another similarly shaped bell crank 18. These bell cranks 16, 18 are pivotally mounted by means of fulcrum pins 19, 19 at opposite corners of the base member 10 at the front of the apparatus. The arms 20, 21 of the bell cranks 16, 18 which do not contain the studs are arranged in superposed relationship on the edge of the base member at the front of the apparatus. For equalizing movement of the two bell cranks, the lower arm 21 is provided with a pin 22 extending upward through an oval slot 23 in the top bell crank arm 20, this pin and slot arrangement being located in line with the center of the apparatus. At the end of each of the superposed arms 20, 21 of the bell cranks 16, 18 are connecting bars 24, 24 pivotally fastened by means of bolts 25, 25 and cotter pins 26, 26. These bars 24, 24 extend along each side of the base member 10 substantially parallel to the sides of the base member and toward the rear of the apparatus. The back stop bar 15, which comprises the third locating member, is pivotally

fastened across the ends of these connecting bars 24, 24 by means of bolts 27 and cotter pins 28. In order that the studs 13, 13 comprising the pair of locating members will be held in close contact with the shoe sole 29 inserted between them, there is provided a spring 30 connecting the arms 33, 17 of the two bell cranks 16, 18.

In the case of apparatus for centering shoe soles, the bell cranks and linkage arms are proportioned and arranged so that the distance moved by the back stop bar 15 varies with respect to the distance moved by the two studs 13, 13 in the same ratio as the ratio which the length of the sole bears to its width.

In using the apparatus of this invention for centering middle soles of shoes, the apparatus is positioned on the platform of a conventional die-press. A sole 29 is inserted between the movable studs 13, 13 and pushed back until progress is stopped by the back stop bar 15. The grooving die 32 of the die-press is then lowered to press the design in the sole, the die is raised, the sole withdrawn, and a new sole is then inserted. This series of operations is continued until every sole is marked and because of the construction of the apparatus herein described each sole is marked in the same relative region no matter what the variation in the size or the shape of the individual soles.

The spring 30 connecting the arms 33, 17 of the bell cranks 16, 18 holds the studs 13, 13 in close proximity to each other. When a shoe sole, or other object, is inserted between the studs 13, 13 these studs are forced apart. The bell cranks 16, 18 move on the fulcrum pins 19, 19 causing the arms 20, 21 of the bell cranks to move back. This backward movement of the arms 20, 21 also moves the back stop bar back by acting on the bar through the connecting bars 24, 24. The arms 20, 21 are kept in alignment and their movement equalized by means of the pin 22 and slot 23 arrangement in the arms 20, 21. Because the back stop bar 15 works in conjunction with the studs 13, 13 the greater the distance between the studs 13, 13 the farther the bar 15 will be moved back thereby providing greater space for larger objects and, conversely, smaller space for smaller objects. As the linkage means between the studs and the back stop bar are rigid mechanical members the space defined by the studs and the back stop bar is always proportional mathematically to the distance between the two studs 13, 13. Thus it is apparent that this invention can be used for locating any article, no matter what its size, in the same relative position with respect to the supporting member.

Fig. 3 shows a shoe sole that has been inserted in the apparatus of this invention and acted upon by a die member (Fig. 2) to form grooves 34. Due to the centering action of the apparatus described in this application the grooves 34 will always be produced in the same relative region of the shoe sole 29 no matter how much the individual soles may vary in size.

The invention has been described in considerable detail as applied to centering middle soles for platform type sandals preparatory to acting thereon by a grooving die but it will be appreciated that the principles herein described may be used in other apparatus of like nature for locating other articles with respect to a supporting member. Also numerous variations and modifications may be made in details of the specific apparatus hereinabove described without

departing from the spirit and scope of the appended claims.

I claim:

1. Apparatus for locating individual shoe sole members of a series of variedly sized, shaped, or sized and shaped shoe sole members with reference to a supporting member, said apparatus comprising at least one movable locating member for laterally locating the shoe sole member 10 and a second movable locating member for longitudinally locating the shoe sole member, one of said locating members being movable by a boundary surface of the shoe sole member and the other of said locating members being movable 15 by movement of the first locating member, said movable members locating the individual shoe sole members in the same relative position with respect to a given area of the supporting member.
2. Apparatus for locating individual shoe sole members of a series of variedly sized, shaped, or sized and shaped shoe sole members with reference to a supporting member, said apparatus comprising at least one movable locating member 20 movable by a boundary surface of the shoe sole member being located for laterally locating the shoe sole member, and a second movable member 25 movable by the movement of the first movable member for longitudinally locating the shoe sole member, said movable members locating the individual shoe sole members in the same relative position with respect to a given area of the supporting member.

3. Apparatus for locating individual articles 35 of a series of variedly sized, shaped, or sized and shaped articles, such as shoe soles, with reference to a supporting member, said apparatus comprising a pair of movable locating members movable by boundary surfaces of the individual 40 article being located, a third movable locating member, and means controlled by movement of said pair of movable locating members for determining the position of said third movable locating member, said three movable locating members locating the individual articles in the same relative position with respect to a given area of the supporting member.

4. Apparatus for locating individual articles of 45 a series of variedly sized, shaped, or sized and shaped articles, such as shoe soles, with reference to a supporting member, said apparatus comprising a pair of locating members movably supported by the supporting member for movement toward and away from each other, a third locating member movably supported by the supporting member for movement transverse to the direction of movement of the pair of locating members, and means controlled by movement of said pair of locating members for determining the position of said third locating member, said three 50 movable locating members locating the individual articles in the same relative position with respect to a given area of the supporting member.

5. Apparatus for locating individual articles of 55 a series of variedly sized, shaped, or sized and shaped articles, such as shoe soles, with reference to a supporting member, said apparatus comprising a pair of movable locating members supported by the supporting member for movement toward and away from each other, means for normally holding said pair of locating members in close relation to each other, a third movable locating member supported by the supporting member for movement transverse to the direction of movement of the pair of locating mem- 70 bers.

bers, and means controlled by movement of said pair of locating members for determining the position of said third locating member, said three movable locating members locating the individual articles in the same relative position with respect to a given area of the supporting member.

6. Apparatus for centering a succession of shoe soles or the like with reference to a device acting thereon, said apparatus comprising a surface for supporting a shoe sole in position to be acted on by the device and a plurality of movable locating members associated with the said surface for properly positioning a shoe sole placed thereon, at least one of said locating members being movable by engagement with an edge portion of the sole and a second one of said locating members adapted to engage a different edge portion of the sole being movable in response to movement of the first said member, the apparatus being so constructed and arranged that the ratio of the movement of one of said locating members to the other said locating member is the same as the ratio of planar dimensions of the sole taken along different lines passing through the points of engagement with the respective locating members.

7. Apparatus for centering a succession of shoe soles or the like with reference to a device acting thereon, said apparatus comprising a surface for supporting a shoe sole in position to be acted on by the device and a plurality of movable locating members associated with the said surface for properly positioning a shoe sole inserted between said members on said surface, said plurality of locating members including two spaced-apart members adapted to engage opposite side portions of the sole and to be moved by engagement with such side portions of the sole and a third locating member adapted to engage an end-portion of the sole to limit insertion of the sole, and means operatively coupling the end engaging locating member with at least one of the side engaging locating members for moving the said members with respect to each other in the same relation as the relation of the width of the 45 shoe sole to its length.

8. Apparatus for locating individual articles of a series of variedly sized, shaped, or sized and shaped articles, such as shoe sole members, with reference to a supporting member, said apparatus comprising at least three movable locating members, and means controlled by movement of one of the locating members for determining the position of the other locating members, said movable locating members locating the individual articles in the same relative position with respect to a given area of the supporting member.

9. Apparatus for locating individual articles of a series of variedly sized, shaped, or sized and shaped articles, such as shoe sole members, with reference to a supporting member, said apparatus comprising at least three movable locating members interconnected for movement in unison so that movement of one locating member determines the position of the others, said movable locating members locating the individual articles in the same relative position with respect to a given area of the supporting member.

10. Apparatus for centering a succession of shoe sole members with reference to a device acting thereon, said apparatus comprising a supporting surface for receiving a sole member, a pair of bell cranks pivotally mounted for movement generally parallel to the said surface and so that one arm of each bell crank engages a different side boundary portion of the sole member inserted therebetween, the other arms of the bell cranks being arranged in overlapping relation and loosely pivoted together in a zone centrally located with respect to the sole centering arms, yielding means normally urging the sole centering arms together, a third member adapted to engage an end boundary portion of the shoe sole member, and linkage means connecting the said third member with the overlapped arms of the bell crank so that all three sole engaging means move in unison in response to insertion of a sole therebetween.

JOHN H. FLINK.
